W.E.CLARK.

BY *Fetherstonhaugh & Co.* ATTY.

UNITED STATES PATENT OFFICE.

WILBERT EDGAR CLARK, OF TORONTO, ONTARIO, CANADA.

TEMPERATURE-BOOSTER FOR HOT-WATER HEATING SYSTEMS.

1,213,460.

Specification of Letters Patent. Patented Jan. 23, 1917.

Application filed December 20, 1915. Serial No. 67,805.

To all whom it may concern:

Be it known that I, WILBERT EDGAR CLARK, a subject of the King of Great Britain, and resident of 28 Adelaide street, West, 5 in the city of Toronto, Province of Ontario, Dominion of Canada, have invented certain new and useful Improvements in Temperature-Boosters for Hot-Water Heating Systems, of which the following is a specification.

10 This invention relates to a temperature booster for hot water heating systems, and the objects of the invention are to increase the temperature and circulation of the water 15 in the system, and it consists essentially of a chamber having two passageways, one controlled by a weighted valve and one controlled by a by-pass valve, all as hereinafter more fully set forth and described in the accompanying specification and drawing.

20 The drawings show a vertical section through an embodiment of the invention.

Referring to the drawing, A represents a 25 casing comprising a cylindrical portion 10, a bottom outlet 11 and a side outlet 12. The top of the cylindrical portion 10 is closed by a removable cover 13 having screw threaded engagement therewith.

30 The chamber is formed with two passageways or ports, one passageway or port 14 being controlled by the weighted valve B and the other passageway or port 15 being controlled by the by-pass valve C.

35 The weighted valve B is conveniently mounted on a rod 16 extending at one end through a guideway 17 which forms part of the bushing 18 around the port 14 and at the other end extending into a guide socket 40 19 on the cover 13.

The by-pass valve C is mounted in a removable cage D which fits into a cylindrical recess 20, the gate being formed with a by-pass passageway 21 which connects the port 45 15 with the removable pan shaped seat 22 which is held in position by the screw threaded plug 23 which when removed permits access to the cage and valve, said plug having screw threaded engagement with the 50 sides of an opening 24 of the by-pass chamber 25.

The combined by-pass passageways in the valve C form a continuous one of substantially L-shape.

The valve C is gravity seated on a removable tapered seat 26. This seat 26 has screw threaded engagement with the walls of an aperture 27 formed above the pan shaped seat 22 and the valve C is formed with a guide stem 28 adapted to fit a guide recess 29 in the upper part of the cage D. To keep the cage D from turning, pins 30 may be provided on the upper part thereof adapted to fit recesses 31 in the casing 10.

To insure close contact of the valve B 65 with the bushing or valve seat 18 a nose or tip 35 of brass or the like may be formed thereon, said tip being firmly attached to the body portion of the weighted valve by means of an anchored member 36 having diverging wings which extend into the body portion 37. This body portion is conveniently formed of readily cast material, such as lead, so that its weight may be adjusted to suit the system in which it is to be used. 75

In hot water heating systems the device is attached to the pipe line which leads to the expansion tank either at the boiler or a point near the expansion tank but below it. When the water in the system is heated by the furnace in the usual way it expands and rises to the booster. The by-pass valve C is seated and the water has no means of escape to the expansion tank until it reaches a pressure, due to expansion from the increased temperature, sufficient to raise or lift the weighted valve B when the surplus water escapes through the valve seat 18 and outlet neck 12 into the expansion tank. When enough water has been released so that the weighted 85 valve B just equals the pressure in the system the said valve falls and seats itself. When the water again falls in temperature the pressure is lowered and the water from the tank flows through the by-pass valve C 90 and forces it up and then flows unrestricted back to the boiler. The amount of weight in the valve B may be regulated to suit the amount of radiation in the system and owing to the cup shape of the valve the amount of 100 weight may be readily adjusted.

The clean out plug 23 permits any oil or

sediment in the system which tends to gum the valve or mechanism to be readily removed.

It will be seen that the by-pass valve C is self contained and can be readily removed from the device by removing the plug 23. This valve C, it will be seen, has a closely fitting tapered brass seat and is absolutely tight, even against air, although it releases very readily under the pressure of the returning water.

As many changes could be made in the above construction and many apparently widely different embodiments of my invention, within the scope of the claims, constructed without departing from the spirit or scope thereof, it is intended that all matter contained in the accompanying specification and drawings shall be interpreted as illustrative and not in a limiting sense.

What I claim as my invention is:

1. A temperature booster for hot water heating systems comprising a cylindrical portion having a bottom outlet neck and a side outlet neck, a main passageway between the outlet necks and a by-pass passageway between said outlet necks, a weighted valve controlling the main passageway, a removable cage member mounted in the by-pass passageway having a passageway therethrough, a cup shaped seat communicating with the bottom of the last mentioned passageway, said combined by-pass passageway forming one of L shape, a removable plug holding the seat and cage member in position, a valve mounted in the cage member and a removable seat for the valve, substantially as described.

2. A temperature booster of the character described comprising, in combination, a valve casing provided with an outlet passageway formed with a valve seat and a separate by-pass passageway for back flow, said by-pass passageway being formed with an enlargement opposite an opening formed in the casing, a weighted valve gravity seated on the valve seat in the outlet passageway, a cage member fitting to the enlargement in the by-pass passageway and being itself formed with two passageways, one of which has a tapered valve seat thereon, a tapered valve fitting the seat and reciprocably held in position thereon, a plug closing the opening in the casing, and a removable member co-acting therewith formed with a recess adapted to connect the two passageways in the cage member, as and for the purpose specified.

3. A temperature booster of the character described comprising, in combination, a valve casing provided with an outlet passageway formed with a valve seat and a separate by-pass passageway for back flow, said by-pass passageway being formed with an

enlargement opposite an opening formed in the casing, a weighted valve gravity seated on the valve seat in the outlet passageway, a cage member formed with two passageways, a valve seat removably mounted in one passageway and having screw threaded engagement with the wall thereof, a valve adapted to fit the seat, a plug closing the opening in the casing, and a removable member co-acting therewith formed with a recess which affords communication between the two passageways and the cage member.

4. A temperature booster of the character described comprising, in combination, a valve casing provided with an outlet passageway formed with a valve seat and a separate by-pass passageway for back flow, said by-pass passageway being formed with an enlargement opposite an opening formed in the casing, a weighted valve gravity seated on the valve seat in the outlet passageway, a cage member fitting to the enlargement and being formed with two passageways, one of which has a valve seat thereon and being also formed with a guide recess opposite the valve seat, a valve adapted to fit the valve seat and having a projection adapted to extend into the recess, a plug adapted to close the opening in the casing, and a removable member co-acting therewith having a recess which affords communication between the two passageways and the cage member.

5. A temperature booster of the character described comprising, in combination, a valve casing provided with an outlet passageway formed with a valve seat and a separate by-pass passageway for back flow, said by-pass passageway being formed with an enlargement opposite an opening formed in the casing, a weighted valve gravity seated on the valve seat in the outlet passageway, a substantially cylindrical shaped cage member fitting to the enlargement, being formed with one passageway extending end to end of the same, and being formed with another passageway extending from the under side and opening at one side, a valve seat removably mounted in said last mentioned passageway, a valve fitted to the seat, a plug member closing the opening in the casing, and a removable member co-acting therewith affording communication between the two passageways in the casing.

6. A temperature booster of the character described comprising, in combination a valve casing provided with an outlet passageway formed with a valve seat and a separate by-pass passageway for back flow, said by-pass passageway being formed with an enlargement opposite an opening formed in the casing, a weighted valve gravity seated in the valve seat in the outlet passageway, a cage member fitting to the enlargement and being

formed with a passageway having a valve seat thereon, a valve reciprocably held in position on said valve seat, a plug closing the opening in the casing and holding the 5 cage member in position and a removable member co-acting with the plug.

In witness whereof I have hereunto set my hand in the presence of two witnesses.

WILBERT EDGAR CLARK.
